RADIO BOMB RELEASE SYSTEM

David G. C. Luck, Princeton, N. J., assignor to
 Radio Corporation of America, a corporation
 of Delaware

Application February 6, 1946, Serial No. 645,912

10 Claims. (Cl. 343—7)

1
 This invention relates to radio bomb release systems and more particularly to improvements in systems of the time from target computing type, such as those described in copending U. S. patent application Serial No. 531,953, filed April 20, 1944, by Royden C. Sanders, Jr., entitled Radio Bomb Release System, now matured to Patent No. 2,416,223. Such systems operate by measuring the range of a selected target from the bomber, and the speed of the bomber with respect to the target, computing the predicted time from target in response to said measurements. The time from target is defined as the period which will be required after a given instant for the bomber to reach a point directly over the target. At a predetermined time from target, depending upon the altitude of the bomber craft, the bomb release mechanism is energized.

Any system which measures the range and speed of a craft with respect to a target by means of radio signals reflected from said target will respond to the true, or slant range, rather than the projection of this distance along the line of flight of the craft. Likewise, the slant speed is measured instead of the speed component along the line of flight. Thus the quotient of the measured range and the measured speed is ordinarily an approximation to the true time from target, and one which becomes increasingly erroneous as the target is approached. The computed time from target may be corrected satisfactorily, within certain limits of slant speed, by using linear approximations to the relationships between slant range at release, slant speed at release, and altitude.

It is the principal object of the present invention to provide methods of and means for computing automatically the time from target in accordance with its exact relationships to slant speed, slant range and altitude, rather than any approximations thereto.

Another object is to provide systems of the described type which automatically take into account the effects of vertical components in the flight of the bomber craft.

Still another object is to provide improved methods of and means for producing an adjustable range lead to enable dropping a bomb a predetermined distance ahead or behind the target.

The invention will be described with reference to the accompanying drawings, wherein:

Figure 1 is a geometrical diagram illustrating the elements of a bomb release problem,

Figure 2 is a schematic block diagram of an embodiment of the present invention,

2
 Figure 3 is a schematic diagram of a modification of the system of Figure 1,

Figure 4 is a graph illustrating variations in frequency of signals transmitted and received in the operation of the system of Figure 2, and

Figure 5 is a schematic diagram of a further modification of the system of Figure 2.

Refer to Figure 1. It is assumed that a bomber, at present at the point 1, is flying toward a point 3 at a distance D from the point 1, and at an altitude H directly over a target at the point 5, at a uniform ground speed G with respect to the point 3. The time from target, i. e. the time which will be required for the craft to reach a point directly over the target, is:

$$(1) \quad T = \frac{D}{G}$$

20
 As mentioned before, the distance D and ground speed (horizontal component of speed) G are not measured directly by radio equipment on the bomber. However, the slant range R, the slant speed S, the altitude H, and the vertical speed V can be measured, as described in detail hereinafter.

$$(2) \quad H = R \sin \alpha$$

and

$$(3) \quad D = R \cos \alpha$$

where α is the target depression angle. The slant speed is:

$$(4) \quad S = G \cos \alpha + V \sin \alpha$$

35
 where V is the vertical component of the speed of the bomber craft taken as positive when directed downward. If the bomber is flying horizontally, V is zero. Eliminating the quantities D, G, and α from Equations 1, 2, 3 and 4, the time from target T is found to be given in terms of the measured quantities R, S, H and V by:

$$(5) \quad \frac{R/R}{T} - S = \frac{H}{T} \left(\frac{H}{T} - V \right)$$

45
 Neglecting the effect of air resistance, as is permissible for moderate altitudes and speeds, the time of fall T_f of a bomb is related to its altitude H and the vertical speed V at the instant of its release as follows:

$$(6) \quad \frac{H}{T_f} - V = \frac{1}{2} g T_f$$

50
 Since the forward velocity of the bomb is the same as that of the aircraft, the release in

occur at a time from target equal to the time of fall to effect a hit, i. e. release should occur when Equations 5 and 6 are satisfied by the same value of $T (= T_f)$.

Equation 5 relates the time from target to the directly measurable variables R , S , V and H without involving any approximations. Under level flight conditions ($V=0$), the relationship (5) becomes:

$$(7) \quad \frac{R}{T} \left(\frac{R}{T} - S \right) = \left(\frac{H}{T} \right)^2$$

and (6) becomes:

$$(8) \quad \frac{H}{T_f} = \frac{1}{2} g T_f$$

In the embodiment of the present invention illustrated in Figure 2, the bomber carries a range measuring device 11 and a speed measuring device 13. The device 11 may be similar to the well known frequency modulation type radio altimeter, but arranged to transmit and receive signals in a generally forward, rather than downward direction. The device 11 provides an electrical output having a magnitude (e. g. current or voltage) proportional to the slant range R of a target toward which it is directed. The speed measuring device also may be of the radio reflection type, utilizing the Doppler effect on the signals transmitted to and received from the target to provide an electrical output proportional to the slant speed S of the bomber relative to the target.

The range measuring device 11 is connected to a sensitivity control 15, which serves to adjust the proportionality of the electrical output to the range. More specifically, the output of the device 11 is a voltage proportional to the range, i. e. a certain number of volts represents a certain number of feet. The control 15 modifies this output to make a different number of volts represent a certain number of feet. This modified output is applied to one pair of input terminals of a wattmeter mechanism 17. It is also applied, together with and in opposition to the output of the speed measuring device 13, to the other pair of input terminals of the wattmeter 17.

The output shaft of the wattmeter 17 is coupled mechanically by a shaft 19 to a biasing device such as a torque motor 21. The torque motor 21 may be an ordinary direct-current meter, and is provided with torque control means 23 for regulating the input to the motor 21 and hence the torque developed by it. The connections to the motor 21 are such that its torque opposes that of the wattmeter 17.

A pair of contacts 25 is coupled to the shaft 19, in such manner that the torque of the wattmeter 17 tends to hold it open, and is adjusted so as to close when the total torque is zero, i. e. that of the wattmeter 17 equals that of the torque motor 21. The contacts 25 are connected to the actuating circuit of a bomb release mechanism, not shown.

The adjustment and operation of the system of Figure 2 are as follows:

The output of the range measuring device 11 is bR , where b is a constant. Similarly, the output of the speed measuring device 13 is cS , where c is also a constant. The sensitivity control 15 modifies the output bR of the range measuring device 11 to provide an output ubR , where u is a factor depending upon the adjustment of the control 15. This is applied to the upper terminals of the wattmeter 17.

The input to the lower terminals of the wattmeter 17 is the difference of the outputs of the control 15 and the speed measuring device 13:

$$ubR - cS$$

and the resulting torque F is proportional to the product of the two inputs:

$$F = d(ubR)(ubR - cS)$$

where d is a constant determined by the design of the wattmeter.

The opposing torque F' provided by the torque motor 21 depends on the adjustment of the torque control 23. As long as $F > F'$, the switch 25 remains open. To close the switch, F and F' must be equal, and

$$d(ubR)(ubR - cS) = F'$$

or dividing both sides by dc^2 ,

$$(9) \quad \left(\frac{ubR}{c} \right) \left(\frac{ubR}{c} - S \right) = \frac{F'}{dc^2}$$

In order for the bomb to strike the target, the switch 25 must be closed to cause release when (from Equation 7)

$$R \left(\frac{R}{T_f} - S \right) = \frac{H^2}{T_f^2}$$

There is an unavoidable time lag T_L in the response of the measuring apparatus and the release mechanism. Accordingly, the condition for closing the contacts 25 becomes:

$$(10) \quad \frac{R'}{T_f + T_L} \left(\frac{R'}{T_f + T_L} - S \right) = \left(\frac{H}{T_f + T_L} \right)^2$$

where R' is the range measured at a time T_L before the desired release. Substituting

$$\frac{1}{2} g T_f^2$$

for H (Equation 8), the condition for release is:

$$(11) \quad \frac{R'}{T_f + T_L} \left(\frac{R'}{T_f + T_L} - S \right) = \frac{1}{4} g^2 T_f^2 \left(\frac{T_f}{T_f + T_L} \right)^2$$

Comparison of Equations 9 and 11 shows that to cause release at the proper instant, the sensitivity control 15 must be adjusted to make:

$$(12) \quad u = \frac{c}{b(T_f + T_L)}$$

and the torque control 23 must be adjusted so that

$$(13) \quad F' = \frac{1}{4} dc^2 g^2 T_f^2 \left(\frac{T_f}{T_f + T_L} \right)^2$$

It is apparent from Equations 12 and 13 that T_f is the only variable in the relations for u and F' , since T_L is a constant of the equipment. Therefore, u and F' are functions solely of H . Thus the controls 15 and 23 may be ganged, as indicated by dash lines 27, and operated by common control means which may be manual, or may be an altitude responsive servo system such as that shown in copending U. S. patent application Serial No. 484,458, now Patent No. 2,443,748, issued June 22, 1948, filed April 24, 1943, by Royden C. Sanders, Jr. et al. and entitled Aircraft Control System. It should be noted that u and F' are different functions of H . The control devices 15 and 23 must be designed with their characteristics tapered accordingly, to enable operation from a common control means.

The range and speed measuring functions may be combined in a single radio system, using but one transmitter and one receiver. Refer to Figure 3, wherein elements corresponding to those

of Figure 2 are designated by corresponding reference characters. A radio transmitter 31 is provided with an antenna 33 and is connected to a frequency modulator 35. The modulator 35 may be of the vibratory variable capacitor type or other known means for varying the frequency of operation of the transmitter 31 in accordance with a modulating signal.

A square wave generator 37 is coupled to the modulator 35, through an adjustable voltage divider 15 and a wave shaping circuit 39. The voltage divider 15 performs the function of the range sensitivity control of Figure 1. The wave shaping circuit converts the square wave which is applied to it to a wave of substantially symmetrical triangular form.

A radio receiver 41 is provided with an antenna 43, and has its output circuit connected to a voltage limiter 45. The receiver 41 is coupled also to the transmitter 33, through a line 44. The output circuit of the limiter 45 is connected to an averaging cycle counter circuit 47. The output of the counter 47 is applied to the upper pair of input terminals of the wattmeter 17. The output circuit of the limiter 45 is connected also to a differential counter circuit 49. The differential counter 49 may be of the type described in U. S. patent application Serial No. 524,794, filed March 2, 1944, by Royden C. Sanders, Jr. et al., entitled Radio Bomb Release System, now matured to Patent No. 2,412,632, and is keyed by the square wave generator 37 to count positive when the square wave is of positive polarity, and to count negative when the square wave is negative. The output of the counter 49 is applied to the lower pair of input terminals of the wattmeter 17.

As in the system of Figure 2, the wattmeter 17 is coupled to the torque motor 21 by the shaft 19, which operates the switch 25. The torque control 23 comprises a variable resistor connected between the torque motor 21 and its power source 22.

In the operation of the system of Figure 3, the output of the square wave generator 37 is modified by the wave shaping circuit to provide a substantially triangular wave voltage. This operates the modulator 35 to cause the frequency of the transmitter to vary accordingly, as shown by the solid line 51 in Figure 4. The mean transmitter frequency is f_0 . The range of variation of frequency is $f_2 - f_1$, and depends upon the amplitude of the input to the modulator 35 and hence upon the adjustment of the voltage divider 15.

Some of the output of the transmitter 33 is transferred directly through the line 44 to the receiver 41. The principal portion of the transmitter output is radiated by the antenna 33. A part of the radiated energy strikes the target and is reflected back to the receiver antenna 43.

The received signal varies in frequency like the transmitted signal, but the variations are delayed by the length of time Δt required for radiation to travel from the bomber to the target and back. In addition, the received signal is increased in frequency by Doppler effect, by an amount Δf proportional to the rate of approach of the bomber toward its target. Thus although the range of variation in frequency of the received signal is the same as that of the transmitted signal, the mean frequency is higher, as shown by the dash line 53 in Figure 4.

The delay of the received signal is:

$$\Delta t = \frac{2R}{v}$$

where v is the velocity of radiation propagation,

approximately 983,600,000 feet per second. The Doppler shift is:

$$\Delta f = \frac{2S}{v} f_0$$

The reflected signal combines in the receiver 41 with the transmitted signal applied through the line 44, producing a beat signal. The beat signal includes a component whose frequency is equal to the difference in frequency between the direct and reflected signals. A part of this difference is that caused by the delay Δt and is:

$$f_R = \frac{df}{dt}$$

where

$$\frac{df}{dt}$$

is the rate of change of transmitter frequency, and is $2(f_2 - f_1) \cdot f_m$, where f_m is the modulation frequency (frequency of the square wave generator 37). Thus

$$f_R = 2(f_2 - f_1) \cdot f_m \cdot \frac{2R}{v}$$

During modulation upsweep (i. e. when the transmitter frequency is increasing) the Doppler shift is in the direction to subtract from the frequency difference caused by delay. The beat frequency is thus

$$f_u = f_R - \Delta f = 2f_m(f_2 - f_1) \cdot \frac{2R}{v} - \frac{2S}{v} f_0$$

During modulation downsweep, the beat frequency is the sum of the range component and the speed component:

$$f_d = 2(f_2 - f_1) \cdot f_m \cdot \frac{2R}{v} + \frac{2S}{v} f_0$$

The counter circuit 47 provides an output current proportional to the average frequency of the beat signal:

$$i_1 = k_1 \frac{f_u + f_d}{2}$$

where k_1 is the sensitivity of the counter in amperes per cycle per second, and is determined by the design of the circuit. Since the average beat frequency is merely the range component f_R , the output is

$$i_1 = k_1 2(f_2 - f_1) \cdot f_m \cdot \frac{2R}{v}$$

As mentioned above, the quantity $(f_2 - f_1)$ is controlled by the voltage divider 15, and it corresponds to the range sensitivity factor u , defined in the description of the system of Figure 2. Since f_m , v , and k_1 are constants:

$$i_1 = u b R$$

The differential counter circuit 49 provides a current comprising two alternate opposed components, i_u and i_d . During modulation upsweep, the component i_u flows, and is proportional to the upsweep beat frequency f_u :

$$i_u = k_2 f_u$$

where k_2 is a constant determined by the circuit design. During modulation downsweep, the component i_d flows, in the opposite direction from i_u ,

$$i_d = k_3 f_d$$

where k_3 is a design constant like k_2 but of a different value.

The average output current of the counter circuit 49 is

$$i_a = \frac{i_u - i_d}{2}$$

since i_u and i_d each flow only half the time. Substituting the expressions for i_u and i_d in terms of range and speed:

$$i_a = \frac{1}{2} \left[k_2 \left[2(f_2 - f_1) f_m \cdot \frac{2R}{v} - \frac{2S}{v} f_0 \right] - k_3 \left[2(f_2 - f_1) f_m \cdot \frac{2R}{v} + \frac{2S}{v} f_0 \right] \right]$$

Rearranging the above,

$$i_a = \left(2(f_2 - f_1) f_m \cdot \frac{R}{v} \right) (k_2 - k_3) - \frac{S}{v} f_0 (k_2 + k_3)$$

The upsweep and downsweep sensitivities k_2 and k_3 of the counter circuit 49 are adjusted so that $(k_2 - k_3)$ is equal to the sensitivity k_1 of the counter 47, and

$$\frac{f_0}{v} (k_2 + k_3)$$

is the factor c defined in the description of the system of Figure 2. Then

$$i_a = ubR - cS$$

and the torque provided by the wattmeter 17 is proportional to the product $i_u i_d = ubR (ubR - cS)$.

As in the system of Figure 2, the range sensitivity u and the torque of the motor 21 are adjusted in accordance with the altitude to cause closure of the switch 25 when the time from target equals the time of fall plus the interval T_L .

Although the systems of Figures 2 and 3 involve no approximations in their operation, and may be fully automatic when used in level flight, they make no provision for any vertical component V in the velocity of the bomber with respect to the target. This may be accomplished, also without approximation, by a modification of the present invention.

Refer to Figure 5, wherein elements corresponding to those of Figures 2 and 3 are designated by corresponding reference characters. The torque motor 21 of the above-described systems is replaced by a second wattmeter mechanism 17' similar to the wattmeter 17, and is connected to an altitude responsive system similar to the above-described range responsive system. The altitude channel includes a receiver 41', like the receiver 41 but provided with an antenna 43' having a downwardly directed response pattern. The limiter 45' is identical with the limiter 45, and the counters 47' and 49' are similar to the counters 47 and 49 respectively.

The square wave generator in the present illustration includes a cam operated periodic switch 55, driven continuously by a motor 51. The switch 55 is connected through the voltage divider 15 to a D.-C. source 59, and cyclically applies the output voltage of the voltage divider 15 to a resistor 61. Thus the voltage across the resistor 61 varies in square wave fashion, with an amplitude dependent on the setting of the voltage divider 15.

The wattmeters 17 and 17' are coupled together by the shaft 19 which carries two sets of contacts 26 connected like a reversing switch between a reversible motor 63 and a power source 65. The contacts 26 are adjusted to energize the motor 63 to run only when the torque of one wattmeter exceeds that of the other, and in a direction depending upon which torque is greater.

The motor 63 is coupled to one input shaft of a differential 67. A constant speed clock motor 69 is coupled to the other input shaft of the differential 67. The output of the differential 67 drives the time from target shaft 27.

A voltage divider 71 is connected across the D.-C. source 59, and its output is applied to one winding of a differential relay 73. The other winding of the relay 73 is connected to the output of the differential counter 49' of the altitude channel.

In the operation of the system of Figure 5, as in that of Figure 3, the counter 47 provides an output $i_u = ubR$, and the differential counter 15 49 provides an output $i_d = ubR - cS$. Now suppose that the shaft 27 is at a position such that the voltage divider 15 is adjusted to make

$$u = \frac{c}{bT}$$

Then the torque F of the wattmeter 17 will be proportional to:

$$i_u i_d = \left(\frac{c}{bT} bR \right) \left(\frac{c}{bT} bR - cS \right)$$

and

$$(14) \quad F \propto \frac{R}{T} \left(\frac{R}{T} - S \right)$$

A pair of resistors 75 and 77 are included in the connections from the counters 47 and 49 to the wattmeter 17 for a purpose to be described hereinafter. These do not affect the present analysis, since they merely alter the constant factor of proportionality of F to

$$R \left(\frac{R}{T} - S \right)$$

The altitude counter 47' operates like the range counter 47, providing an output i_1' bearing the same sort of relationship to the altitude as the current i_u bears to the range, i. e.

$$i_1' \propto \frac{H}{T}$$

45 Similarly, the output of the differential counter 49' is i_d' , where

$$i_d' \propto \left(\frac{H}{T} - V \right)$$

50 The torque of the wattmeter 17' is thus:

$$(15) \quad F' \propto \frac{H}{T} \left(\frac{H}{T} - V \right)$$

The overall sensitivities of the range and altitude channels are made to correspond so that $F = F'$ when

$$\frac{R}{T} \left(\frac{R}{T} - S \right) = \frac{H}{T} \left(\frac{H}{T} - V \right)$$

which is Equation 5.

55 Thus so long as the shaft 27 is in a position corresponding to the present time from target, T , $F = F'$ and the motor 63 is deenergized.

The clock motor 69, through the differential 67, drives the shaft 27 at a constant speed corresponding to the passage of time. Thus, if the shaft 27 is set initially at the position corresponding to the then time from target, the clock motor 69 will rotate it to continue to correspond to the predicted time from target. If the shaft 27 does not correspond to the time from target, the torque of one of the wattmeters 17 and 17' will overcome that of the other, energizing the motor 63 and causing it to rotate in the direction required to set the shaft 27, by way of the differential 67, to its proper position. With this ar-

angement, temporary failure of the range signal as a result of fading will not prevent operation or cause serious error, since the equipment will continue to operate as a clock indicating time from target, on the basis of the last available data.

Since the operation of the counters and the servo is subject to an unavoidable time lag T_{L_1} , the servo will not set the output of potentiometer 15 to present time from target T as determined by present range R but rather to past time from target $T+T_{L_1}$ as determined by radar measurement of the corresponding past range R' . By suitable setting with respect to the resistance-rotation characteristic of potentiometer 15, the servo shaft position may nevertheless represent present time from target T.

A plane which is now at altitude H and descending at constant vertical velocity V and will cross over the target after a time T, will cross at an altitude H_0 where

$$(16) \quad H_0 = H - VT$$

Altitude, vertical speed and time of fall of a bomb released from this plane are always related by

$$(17) \quad H_r - VT_f = \frac{1}{2} g T_f^2$$

where H_r is the altitude at release. If the bomb is to hit the target, its time of fall must equal the time from target at release, and

$$(18) \quad H_r - VT_f = H_0$$

The equipment measures altitude H' at time from target $T+T_{L_1}$, and actual release should occur at time $T-T_{L_2}$, where T is the time indicated by the position of the shaft 21 when the actuating condition for the release relay is fulfilled and T_{L_2} is the time lag in operation of the release relay and release mechanism. Use of these quantities in Equations 16, 17 and 18 in combination gives as the release condition

$$(19) \quad \frac{H'}{T+T_{L_1}} - V = \frac{1}{2} g \frac{(T-T_{L_2})^2}{T+T_{L_1}}$$

which replaces the simpler Equation 6 developed earlier for the case of zero time lags.

The output of the differential counter 49' to the upper coil of the differential relay 73 is, in view of the time lag T_{L_1} ,

$$i_{2a} \frac{H'}{T+T_{L_1}} - V$$

The voltage divider 71 is designed so that its output causes a current

$$i_{2a} \frac{(T-T_{L_2})^2}{T+T_{L_1}}$$

to flow in the lower coil of the relay 73, where T_{L_2} is the time interval required for operation of the relay 73 and the bomb release mechanism. The proportionality of i_2 to T is made such that $i_2 = i_1'$ when

$$(20) \quad \frac{H'}{T+T_{L_1}} - V = \frac{1}{2} g \frac{(T-T_{L_2})^2}{T+T_{L_1}}$$

It is desirable under some conditions to drop a bomb so as to fall a predetermined distance ahead of or behind the target rather than on the target. The distance by which the bomb is to fall short of the target is referred to herein as range lead. In the system of Figure 5, adjustable range lead is provided by a voltage divider 81, connected across the output of the voltage divider 15. The output of the range lead control

81 is applied to both input circuits of the wattmeter movement 17 through resistors 83 and 85 respectively.

The resistors 83 and 85, as well as the previously mentioned resistors 15 and 71, are much higher in resistance than the respective input circuits of the wattmeter 17. With this arrangement, the current in the upper input circuit of the wattmeter 17 is proportional to the sum of the output i_1 of the counter 47 and a current i_3 determined by the setting of the voltage divider 81 and the position of the voltage divider 15. Similarly, the input to the lower terminals of the wattmeter 17 is proportional to the sum of the output i_2 of the counter 49, and the current i_3 . The torque of the wattmeter 17 is thus increased or decreased by an amount such as to cause the bomb to fall short or fall beyond the target by a distance depending only upon the adjustment of the voltage divider 81, and independent of the altitude or time from target.

Throughout the above description, it has been assumed that the effects of air resistance on the trajectory of the bomb are negligible. However, at high bomber speeds and moderate altitudes, the bomb does not remain directly under the aircraft during its fall, but "trails," or falls behind the bomber. The trail is a function substantially only of the air speed of the bomber and the ballistic characteristics of the bomb itself. Thus, for a given type of bomb and operating air speed, a certain trail angle β should be included in the computations for bomb release.

In the system of Figure 5, a voltage divider 87 is connected across the output of the altitude counter 41', and is coupled to the upper and lower terminals of the wattmeter 17 through resistors 89 and 91 respectively. These resistors, like the resistors 83 and 85, are much higher in resistance than the wattmeter itself. Thus the effect of the voltage divider 87 and the resistors 89 and 91 is to add a current i_4 , proportional to the output i_{1a} of the counter 41' to the currents i_1 and i_2 respectively in the wattmeter 17. This alters the torque of the wattmeter 17 in accordance with the adjustment of the voltage divider 81, as if the range R were decreased by an amount $H \sin \beta$, and thus effects compensation for trail.

I claim as my invention:

1. In a radio bomb release system including means responsive to the slant range of a target from a bomber craft to provide an electrical output proportional to said slant range, and means responsive to the slant speed of said bomber with respect to said target to provide a second electrical output proportional to said slant speed, means for adjusting the proportionality of said first output to said slant range, means responsive to said adjusted first output and to said second output to produce a force proportional to the product of said adjusted first output by the difference of said adjusted first output and said second output, means providing a second force, and means responsive to equality of the magnitudes of said first and second forces to effect bomb release.

2. In a radio bomb release system including means responsive to the slant range of a target from a bomber craft to provide an electrical output proportional to said slant range, and means responsive to the slant speed of said bomber with respect to said target to provide a second electrical output proportional to said slant speed, means for adjusting the proportionality of said first output to said slant range, means responsive to said adjusted first output and to said second out-

put to produce a force proportional to the product of said adjusted first output by the difference of said adjusted first output and said second output, and means responsive to the attainment by said force of a predetermined magnitude to effect bomb release.

3. In a radio bomb release system including means responsive to the slant range of a target from a bomber craft to provide an electrical output proportional to said slant range, and means responsive to the slant speed of said bomber with respect to said target to provide a second electrical output proportional to said slant speed, means for adjusting the proportionality of said first output to said slant range, means responsive to said adjusted first output and to said second output to produce a force proportional to the product of said adjusted first output by the difference of said adjusted first output and said second output, means providing an adjustable second force, and means responsive to the attainment of equality by said forces to effect bomb release.

4. In a radio bomb release system including means responsive to the slant range of a target from a bomber craft to provide an electrical output proportional to said slant range, and means responsive to the slant speed of said bomber with respect to said target to provide a second electrical output proportional to said slant speed, means for adjusting the proportionality of said first output to said slant range in accordance with a predetermined function of the altitude of said craft, means responsive to said adjusted first output and to said second output to produce a force proportional to the product of said adjusted first output by the difference of said adjusted first output and said second output, means providing a second force which is a second predetermined function of the altitude of said craft, and means responsive to the attainment of equality by said forces to effect bomb release.

5. In a radio bomb release system including means responsive to the slant range of a target from a bomber craft to provide an electrical output proportional to said slant range, and means responsive to the slant speed of said bomber with respect to said target to provide a second electrical output proportional to said slant speed, means for adjusting in substantially reciprocal relation to the time from target at which a bomb is to be released the proportionality of said first output to said slant range, means responsive to said adjusted first output and to said second output to produce a force proportional to the product of said adjusted first output by the difference of said adjusted first output and said second output, means providing a second force adjustable substantially in proportion to the time from target at which a bomb is to be released, and means responsive to the attainment of a predetermined difference between said forces to effect bomb release.

6. A bomb release system including frequency modulated radio transmitter means and receiver means providing a beat signal varying cyclically in frequency about a mean frequency proportional to the slant range of a bomber craft from a selected target, throughout a band whose width is proportional to the slant speed of said bomber with respect to said target, averaging counter means responsive to said beat signal to provide an output proportional to said slant range, counter means responsive differentially to said beat signal during increase and decrease of frequency

of said transmitter means to provide an output differing from that of said averaging counter by an amount proportional to said slant speed, means for adjusting the rate of change of frequency of said transmitter means to adjust the proportionality to said slant range of said counter outputs, means responsive to both of said counter outputs to produce a force proportional to their product, and means responsive to the attainment by said force of a predetermined value to effect bomb release.

7. A bomb release system including frequency modulated radio transmitter means, radio receiver means providing a beat signal varying cyclically in frequency about a mean frequency proportional to the slant range of a bomber craft from a selected target, throughout a band whose width is proportional to the slant speed of said bomber with respect to said target, averaging counter means responsive to said beat signal to provide an output proportional to said slant range, differential counter means responsive differentially to said beat signal during increase and decrease of frequency of said transmitter means to provide an output differing from that of said averaging counter by an amount proportional to said slant speed, means for adjusting the rate of change of frequency of said transmitter means to adjust the proportionality to said slant range of said counter outputs, and means responsive to both of said counter outputs to produce a force proportional to their product; further radio receiver means providing a second beat signal, corresponding to the altitude and vertical velocity of said bomber like said first beat signal corresponds to said range and said speed; further averaging counter means responsive to said second beat signal to provide an output proportional to said altitude, further differential counter means responsive to said second beat signal to provide an output differing from that of said further averaging counter by an amount proportional to said vertical velocity, means responsive to the outputs of both of said further counters to produce a second force proportional to their product, and servo means including an output shaft and responsive to the difference between said first and second forces to control said means for adjusting said rate of change of frequency of said transmitter and thereby maintain said output shaft at a position corresponding to the time interval required for said craft to reach said target.

8. A bomb release system including frequency modulated radio transmitter means, radio receiver means providing a beat signal varying cyclically in frequency about a mean frequency proportional to the slant range of a bomber craft from a selected target, throughout a band whose width is proportional to the slant speed of said bomber with respect to said target, averaging counter means responsive to said beat signal to provide an output proportional to said slant range, differential counter means responsive differentially to said beat signal during increase and decrease of frequency of said transmitter means to provide an output differing from that of said averaging counter by an amount proportional to said slant speed, means for adjusting the rate of change of frequency of said transmitter means to adjust the proportionality to said slant range of said counter outputs, and means responsive to both of said counter outputs to produce a force proportional to their product; further radio receiver means providing a second

13

beat signal, corresponding to the altitude and vertical velocity of said bomber like said first beat signal corresponds to said range and said speed; further averaging counter means responsive to said second beat signal to provide an output proportional to said altitude, further differential counter means responsive to said second beat signal to provide an output differing from that of said further averaging counter by an amount proportional to said vertical velocity, means responsive to the outputs of both of said further counters to produce a second force proportional to their product, servo means including an output shaft and responsive to the attainment of equality by said first and second forces to control said means for adjusting said rate of change of frequency of said transmitter means and thereby maintain said output shaft at a position corresponding to the time interval required for said craft to reach said target; means responsive to the position of said output shaft to provide an output current substantially proportional to said time interval, and relay means responsive differentially to said last-mentioned current and to the output current of said second averaging counter to effect bomb release upon the attainment of a predetermined magnitude relationship between said two last-mentioned currents.

9. In combination in a bomb release system, 30 means responsive to slant range and slant speed,

14

respectively providing voltages of magnitudes proportional respectively to slant range and slant speed, a wattmeter mechanism including two input circuits, means applying said range-proportional voltage to one of said input circuits, means applying said speed proportional voltage and said range-proportional voltage in opposition to each other to the other of said input circuits, and means determining the attainment of a predetermined torque by said wattmeter mechanism.

10. The invention as set forth in claim 9, including means controlling the proportionality of said range-proportional voltage to slant range in accordance with altitude, and means controlling the value of said predetermined torque in accordance with said altitude.

DAVID G. C. LUCK.
